(57) **CLAIM**

The ornamental design for a pendant, as shown and described.

DESCRIPTION

FIG. 1 is a perspective view of a pendant, showing the new design in a closed position;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is bottom plan view thereof; and,

FIG. 8 is a front elevational exploded view thereof, shown in an opened position.

The broken lines represent environmental structure as well as portions of the pendant that form no part of the claimed design.
